PERIPHERAL DIAMOND GRINDING WHEEL

Edward Van der Pyl, Holden, Mass., assignor to
 Norton Company, Worcester, Mass., a corpora-
 tion of Massachusetts

Application December 1, 1941, Serial No. 421,152

13 Claims. (Cl. 51—206)

The invention relates to diamond grinding wheels, particularly of the metal bonded type. This application is a continuation in part of my copending application Serial No. 338,870 filed June 5, 1940. This application also discloses and contains certain subject matter common to it and my copending application Serial No. 421,151 filed concurrently herewith which discloses another species of my invention, and it is in my present application that such subject matter common to all species is generically claimed.

One object of the invention is to provide a diamond grinding wheel bonded with metal bond with a resinoid center or support. Another object of the invention is to provide an improved construction permitting a tight union between the metal bonded ring-like grinding portion and the resinoid center or support. Another object of the invention is to provide a grinding wheel of light weight which readily dissipates heat. Other objects will be in part obvious or in part pointed out hereinafter.

The invention accordingly consists in the features of construction, combinations of elements, arrangements of parts, and in the several steps and relation and order of each of said steps to one or more of the others thereof, all as will be illustratively described herein and the scope of the application of which will be indicated in the following claims.

In the accompanying drawing, in which two of many possible embodiments of the mechanical features of this invention are shown, and in which every view is an axial sectional view,

Figure 1 shows a mold filled with metal powder before the first pressing operation;

Figure 2 shows a metal ring produced by the pressing operation of Figure 1;

Figure 3 shows the mold of Figure 1 containing the metal ring of Figure 2 after it has been reduced in diameter, and containing also loose diamonds and metal powder to form the diamond abrasive portion;

Figure 4 shows another mold containing the metal ring with the metal bonded diamond portion produced by the pressing operation illustrated in Figure 3 after the ring has been sintered and machined, and also containing a loosely pressed disk of, for example "A" stage resin;

Figure 5 shows the completed article; and

Figure 6 illustrates a modification.

I provide a quantity of diamond fragments of small size, such as abrasive grit sizes 80 to 400 where the wheel is to contain diamonds as the abrasive, and where the abrasive is to be metal-

bonded, I also provide a quantity of metal powder. Within the scope of this invention, any other abrasive such as fused alumina, emery, corundum, silicon carbide, boron carbide, tungsten carbide or titanium carbide may be used. Also, within the scope of this invention, any metal bond may be employed although I prefer to use one of the bonds of my own prior Patent Reissue No. 21,165, preferably copper and tin, using about 20% of tin and the remainder of copper. Other combinations mentioned in this reissue patent are copper-nickel, copper-aluminum, copper-manganese, and copper-beryllium. Other metal bonds which have been suggested, such as iron, aluminum-silicon, aluminum-copper, and aluminum-iron, might be employed. So also in certain cases I might use such bonds as cobalt or nickel. I may also use any of the bonds described in or within the scope of my Patent No. 2,238,351, such as 25% each of copper, tin, iron and nickel. With such materials I then proceed preferably as follows:

Referring now to Figure 1, I provide a mold comprising an outer mold ring or band 10, an inner mold ring 11, an annular bottom plate 12, and an annular top pressing plate 13. I fill the annular space between these four parts with the desired metal powder or mixture of metal powders 14. I then put the mold in a hydraulic press 30 and press with a pressure of the order of five to ten (short) tons to the square inch. I then strip the mold and remove the pressed article and place it in a suitable chuck of a lathe and, where it is to be provided with an abrasive portion on its outer cylindrical periphery, I then remove metal on the periphery to reduce the diameter of the ring. The amount of metal taken off should slightly exceed the ultimate radial thickness of the abrasive portion of the final article. Figure 2 35 shows the metal ring 15 after it has been pressed and turned on a lathe.

I now reinsert the ring 15 in the same mold, as illustrated in Figure 3, leaving an annular space between the pressed metal ring 15 and the outer mold ring 10 which I now fill with a mixture of diamonds and metal powder 17, using preferably the same metal powder or combination of metal powders as in the case of the mixture 14. Various concentrations of diamonds or other abrasive 40 may be used but satisfactory results are obtained with 25% by volume of diamonds. I can make a satisfactory commercial article using as low as 6 1/4% of diamonds by volume.

I then replace the mold in the hydraulic press 45 and again press, this time with a pressure of the

order of from 25 to 50 tons to the square inch. In this pressing operation, the height of the ring 15 diminishes to about one half. The diamond metal bond mixture 17 is compressed to about one over 2.5 times its original volume, as shown in Figure 3. The highly compressed ring 15a and the compressed abrasive portion 17a constitute an integral piece. I then take the metal ring 15a with the integral abrasive portion 17a to a sintering furnace and sinter at a temperature of around 600° C. (for the 20% tin, 80% copper mixture) for a period of two hours. This sinters the powders to form a homogeneous, integral article of great strength. For other metals and metal combinations, a satisfactory sintering temperature is one just below the melting point of the metal or of the final alloy. It will be noted that the temperature used for the copper-tin mixture is above the melting point of the tin although it is well below the melting point of copper. This sintering should preferably be done in a reducing or neutral atmosphere.

The above-described sequence of steps is illustrative of those that I prefer to employ where the abrasive grains are metal-bonded and where the grinding wheel is to grind on an outer or peripheral face and hence where the stress imposed by the grinding action upon the ultimate support for the ring-like abrasive element is in a general radial direction; for an illustrative and preferred sequence of steps to make up a ring-like abrasive element that has its abrasive portion on a different face, such as a side face, and hence where the reaction from the grinding operation upon the center or support for the ring-like member is generally in the direction of the axis of the wheel, reference may be made to my above-mentioned copending application, Serial No. 421,151.

I then machine the ring on that face or portion thereof at which it is to be attached to the center or support, and in this illustrative embodiment I hence machine the ring 15a on the inside face (the outside face bearing the abrasive portion 17a as above described) to give it a shape preferably as shown in Figures 4 and 5. As therein disclosed, the inside face or attaching portion of the ring has an inwardly projecting portion 20 and an annular dovetailed portion 21. There is thus provided on the inside of the ring 15a a pair of internal frusto-conical surfaces 22 and 23 whose elements in the preferred embodiments make angles of 20 degrees to the cylindrical periphery of the abrasive metal bonded grinding portion 17a. The annular dovetail 21, in turn, has surfaces 24 and 25 which are external frusto-conical surfaces the elements in the preferred embodiments of which make angles of 20 degrees to a radial plane bisecting the dove tail 21. Thus the angle between surfaces 22 and 24 and between surfaces 23 and 25 is 90 degrees, although this angle may be varied. So also in each case the angle of the frusto-conical surfaces to the cylindrical periphery and the radial plane respectively may vary preferably between 15 degrees and 45 degrees. Within these limits the dove tail 21 is very strong and also when inter-engaged, as hereinafter described, with the moldable and curable resinoid mix to form the center or support, the change in volume, as by shrinkage, of the resinoid during curing coacts with these angles so that the shrinkage of the resin axially substantially balances the radial shrinking.

I then provide a mold, as shown in Figure 4. This mold may consist of an outer mold ring 30, 75

a bottom plate 31, a top plate 32, and a central arbor 33 fitting in central holes 34 and 35, respectively, provided in the plates 31 and 32. From a mixture of uncured resinoid and suitable filler such as asbestos, using a considerable amount of filler, for example, 40% by weight, I press a disk 36 having an axial hole 37 of the same size as the holes 34 and 35. I place this in the mold of Figure 4 inside of the ring 15a in the position shown. I then press with a pressure of the order of 4000 pounds to the square inch which substantially closes the mold. That is to say, the uncured resin flows under the dovetail 21 and against the surfaces 22 and 24 and also over and into contact with the surfaces 23 and 25 and a small layer of it remains on top of the ring 15a, which small layer can readily be trued off. I then remove the article from the mold and cure it at resin curing temperatures. The resin which I also refer to herein as "resinoid" may be phenol formaldehyde or aniline formaldehyde or any one of the alkyd resins or shellac or rubber or methyl methacrylate, styrene or other transparent resin material. The curing temperature and time for phenol formaldehyde resin (having hexamethylene tetramine hardening agent) is around one and one-half hours at 175° C.

The final article is shown in Figure 5 and comprises a cured center 36a, an annular metal portion or ring 15a having its attaching portion or face modified or shaped to provide or to comprise an annular dovetail 21 and an annular triangular portion 20 integral with the metal bonded diamond grinding portion 17a, the resinoid center 36a having a central hole 37.

It might be thought that any interlocking arrangement between the ring 15a and the center 36a might be successfully adopted but such is not the case. I have discovered that recessed and projecting portions which are square in cross section do not give the results; this is because the resinoid, when its volume change is by shrinkage, simply shifts its square projecting parts freely relative to the recesses in the metal part. The use of an annular V shaped portion 20 on the ring 15a which is triangular in cross section in combination with an adjacent dovetail such as 21 gives a firm interlock with the resinoid into which they project and by which they are enveloped. During the heat treatment the resinoid shrinks and if merely cylindrical surfaces were provided in the ring 15a and on the center 36a, these parts would shrink apart, leaving a space. But as the resinoid shrinks inwardly in a radial direction, it also shrinks together in an axial direction and, therefore, moves down the surfaces 22 and 23 without separation. This action causes a firm pressure to be exerted against the dovetail 21 which holds the parts rigidly interlocked. The portions of the resinoid near the surfaces 24 and 25 are under stress in the final article.

By reference to Figure 5 it will be seen that the surfaces 23-25 to one side of a central horizontal plane form a recess and comprise one set of re-entrant angularly inclined surfaces and the surfaces 22-24 form also a recess and comprise another set of angularly inclined surfaces which is on the other side of the just-mentioned horizontal plane. Also it will be noted that the angular recesses which they form face in opposite directions, thus to receive more certainly the two portions of resinoid that are pressed into them by the stresses acting within the resinoid during curing. These stresses act in effect to substan-

tially wedge or force each of the two portions of the resinoid more tightly into its recess, for, as above stated, there is no detrimental separation between these resinoid portions and the surfaces 22 and 23. The above-mentioned firm pressure exerted against the dovetail 21 presses the portions of the resinoid against the surfaces 24 and 25, these portions being under stress as above stated and thus also no detrimental separation takes place between them and their respectively engaged surfaces 24 and 25. The surfaces 22 and 23 form an angle whose apex is directed toward the axis of the wheel and the axially directed stresses in the resinoid caused during curing, move the two opposed portions of the resinoid toward each other and respectively against these inclined surfaces 22 and 23; a substantially similar action takes place with respect to the two inclined surfaces 24—25 which make an angle whose apex is directed away from the axis of the wheel. Thus it will be seen that I am enabled to make use of forces or stresses created in the resinoid undergoing curing, for taking part in effecting a reliable junction of the resinoid with the attaching portion of the metal ring; these stresses or forces result primarily from change such as shrinkage in volume that the resinoid undergoes during curing.

Referring to Figure 6, a modification is illustrated comprising a center 36b, a metal annulus or base 15b and an abrasive portion 17b which can be made by the method already described and which differs from the embodiment of Figures 1 to 5 only in omitting the annular dovetail 21. This construction is found to be satisfactory for thick wheels, but for thin wheels the use of the dovetail is found to be preferable.

Its action in effecting a junction between the resinoid center or support and the metal ring will be understood from what is set forth above in connection with Figure 5, particularly with respect to the inclined surfaces 20 and 23 of Figure 5, for in the modification of Figure 6 counterparts of those two surfaces 22—23 are employed and in the illustration they are extended to intersect, forming an angle whose apex is directed toward the axis of the wheel.

The final article is of light weight because a large part of it consists of a resinoid center 36a, but the heat of grinding is conducted into a relatively large metal ring 15a which makes the wheel cool and free-cutting. The combination of the resinoid center, the metal ring, and the abrasive portion thus gives a light weight, cool-cutting grinding wheel. It will be noted that no diamond abrasive will be wasted since the wheel will grind until the last diamond has disappeared from the portion 17a. In other words, the entire portion 17a can be used up. This is rendered possible by first pressing the ring 15 under light pressure, then compressing this ring 15 with the abrasive metal bond, and abrasive particles under high pressure, thus producing a firm metallurgical union between the parts, and forming the mechanical interlocking portion on the attaching face or portion of the metal ring where there is no abrasive.

It will thus be seen that there has been provided by this invention an article and a method in which the various objects hereinabove set forth together with many thoroughly practical advantages are successfully achieved. As various possible embodiments might be made of the mechanical features of the above invention and as the art herein described might be varied in vari-

ous parts, all without departing from the scope of the invention, it is to be understood that all matter hereinbefore set forth or shown in the accompanying drawing is to be interpreted as illustrative and not in a limiting sense.

5 I claim:

1. A peripheral abrasive wheel comprising a metal ring being, except for possible minor impurities, all metal in a base part and metal bonded abrasive in a peripheral part, said two parts being integrally united and constituting a jointless unit, the base part having a pair of internal frusto-conical surfaces whose elements make angles of between fifteen and forty-five degrees with the peripheral surface, an annular dovetail constituting an integral part of the base part whose sides are external frusto-conical surfaces whose elements make angles between fifteen and forty-five degrees with the radial plane bisecting the dovetail, and a center of cured organic material in contact with all of said frusto-conical surfaces and shrunk against them forming an integral article with no gap anywhere between the parts.

25 2. The method of making a grinding wheel comprising the steps of preforming a metal annulus having a rim of metal bonded abrasive grains and a central V-shaped annular portion projecting inwardly from a median plane of the annulus and thereafter pressing an uncured plastic resinoid body in position within said annulus and causing the resinoid to flow into full supporting contact with said V-shaped portion, and heating and curing the resinoid and thereby causing the curing shrinkage of the resinoid to provide a rigid and firm union between the resinoid body and the annulus supported thereby.

3. Method of making an abrasive wheel which comprises pressing a metal ring from metal powders under low pressure, placing said ring in a mold with an outer mold band slightly larger in its inside diameter than the outside diameter of said metal ring, filling the space between the metal ring and the mold band with a mixture of comminuted abrasive and metal powder, then pressing said ring axially and at the same time compressing said metal powder and metal abrasive under high pressure to form an integral article consisting of metal ring with an abrasive periphery, then sintering the article thus produced by heat, then machining the inside of the sintered ring to form an annular internal dovetail merging with a pair of internal frusto-conical portions formed on the ring, the elements of said frusto-conical portions making an angle between fifteen and forty-five degrees with a cylindrical surface coaxial with said ring, then pressing uncured organic material inside of said ring around said annular dovetail and into contact with said frusto-conical surfaces and curing said organic material to form an integral jointless body, the cured organic material being in stress adjacent the dovetail.

4. In a method of making an abrasive wheel which has a metal ring provided with an abrasive surface and an attaching portion, and a resinoid supporting member for said ring, the steps which comprise modifying the attaching portion of the metal ring to form at least two inclined surfaces for interaction with the resinoid material, placing the modified ring and an uncured resinoid mix in a mold with said inclined surfaces exposed to the resinoid mix and with the angle subtended by said inclined surfaces extending in a direction

related to subsequent shrinkage of the mix to cause the portions of the mix respectively engaging said inclined surfaces to be forced toward each other and respectively against said inclined surfaces, pressing the mix relative to said supporting portion of the ring to flow the mix into supporting contact with said inclined surfaces, and heating the mix to cure it and to cause the forces of shrinkage during curing of the mix to press the portions thereof respectively engaging said inclined surfaces thereagainst.

5. In a method of making an abrasive wheel that has a metal ring provided with an abrasive surface and an attaching portion, and a resinoid supporting member for said ring, the steps which comprise, modifying the attaching portion of the metal ring to form at least two inclined surfaces making an angle whose apex is directed toward the axis of the wheel, placing the ring and an uncured resinoid mix in a mold with said inclined surfaces exposed to the resinoid mix so that respective portions of the mix engage said surfaces to be forced toward each other and respectively against said inclined surfaces by the forces exerted by subsequent shrinking of the resinoid in an axial direction, pressing the mix against said supporting portion of the ring to flow the mix into supporting contact with said inclined surfaces, and heating the mix to cure it and to cause the forces of shrinkage during curing of the mix to press the portions respectively engaging said inclined surfaces thereagainst to maintain tightness of engagement therewith.

6. In a method of making an abrasive wheel that has a metal ring provided with an abrasive surface and an attaching portion, and a resinoid supporting member for said ring, the steps which comprise, modifying the attaching portion of the metal ring to form at least two inclined surfaces making an angle whose apex is directed away from the axis of the wheel, placing the ring and an uncured resinoid mix in a mold with said inclined surfaces exposed to the resinoid mix so that respective portions of the mix engage said surfaces to be forced toward each other and respectively against said inclined surfaces by the forces exerted by subsequent shrinking of the resinoid in an axial and radial direction, pressing the mix against said supporting portion of the ring to flow the mix into supporting contact with said inclined surfaces, and heating the mix to cure it and to cause the forces of shrinkage during curing of the mix to press the portions respectively engaging said inclined surfaces thereagainst to maintain tightness of engagement therewith.

7. In a method of making an abrasive wheel that has a metal ring that has an abrasive surface and an attaching portion presenting a ring-shaped face directed in a general direction toward the axis of the wheel, the steps which comprise modifying the said face to form thereon opposed axially spaced sets of re-entrant angularly inclined surfaces, placing the modified ring and an uncured resinoid mix in a mold with the said modified face exposed to the mix and with said opposed re-entrant angularly inclined surfaces exposed to the mix so that subsequent shrinkage of the mix forces the resinoid into the opposed angularities to grip the intervening material of the ring, pressing the mix to flow the mix against said modified face and into the angularities of said opposed sets of re-entrant angularly inclined surfaces, and heating to cure

the said mix and to cause shrinkage during curing of the latter to force the resinoid into said opposed angularities to effect gripping of the intervening portion of the ring.

8. An abrasive wheel comprising a metal ring having an abrasive portion and an attaching portion, and a resinoid supporting member for said ring, said attaching portion of the metal ring having thereon at least two inclined surfaces for interaction with the resinoid material portions of which are respectively engaged with said inclined surfaces, the angle subtended by said inclined surfaces extending in a direction relative to the direction of shrinkage of the resinoid of said supporting member during curing to make the forces resulting from shrinkage press said portions respectively engaging said inclined surfaces thereagainst.

9. An abrasive wheel as claimed in claim 8 in which the inclined surfaces are positioned relative to each other and to the axis of the ring so that the apex of said angle is directed toward the axis of the wheel, whereby shrinkage in an axial direction during curing in effect draws said two portions of the resinoid material toward each other to maintain tightness of engagement thereof with their respectively engaged inclined surfaces.

10. A grinding wheel as claimed in claim 8 in which said inclined surfaces are positioned relative to each other and to the axis of said ring so that the apex of said angle subtended thereby is directed away from the said axis, whereby shrinkage in both radial and axial directions of the resinoid material during curing effects tightness of engagement of said resinoid portions with their respectively engaged inclined surfaces.

11. An abrasive wheel comprising a metal ring having an abrasive portion and an attaching portion, and a resinoid supporting member for said ring, said attaching portion extending in the general direction toward the axis of the wheel and having opposed sets, spaced in the general direction of the axis, of re-entrant angularly inclined surfaces for interaction with the resinoid material portions of which extend into engagement respectively with said sets of re-entrant inclined surfaces and are in engagement with the latter, the inclinations of said surfaces and the respective angularities formed by each of said sets being in respective directions relative to axial shrinkage during curing of the material of the resinoid of said supporting member to make the forces resulting from shrinkage press portions of the resinoid supporting member respectively into said angularities to effect a gripping therebetween of the intervening portions of said metal ring and to effect tightness of engagement of portions of the resinoid of said supporting member with their respectively engaged inclined surfaces.

12. An abrasive wheel comprising a metal ring having an abrasive portion and an attaching portion, and a resinoid supporting member for said ring, said attaching portion of the metal ring having at least two surfaces that are at an angle to each other and form therebetween an open annular space which, because of the angle between said surfaces, is of substantially tapering cross-section, said resinoid supporting member having annular portions of the resinoid thereof entered into said space and respectively engaged with said two surfaces, the said surfaces being positioned relative to the direction of stresses caused in the resinoid of said supporting member

by and during curing of the resinoid thereof to make said stresses press said annular portions of the resinoid into said space of tapering cross-section to effect gripping engagement of said annular resinoid portions respectively against said two surfaces, the cured resinoid material being in stress in the portions thereof engaging said two surfaces.

13. In a method of making an abrasive wheel that has a metal ring provided with an abrasive surface and an attaching portion, and a resinoid supporting member for said ring, the steps which comprise modifying the attaching portion of the metal ring to form thereon at least two surfaces that are at an angle to each other to form an open annular space which, because of the angle between said surfaces, is of substantially tapering cross-section, placing the modified ring and an

5 uncured resinoid mix in a mold with said surfaces and said open annular space exposed to the resinoid mix in a direction related to the stresses caused in the resinoid by and during subsequent curing thereof to make said stresses press the resinoid into said space of tapering cross-section and against said surfaces, pressing the uncured resinoid mix to flow the mix into full supporting contact with said two surfaces and into said 10 space of tapering cross-section, and heating the mix to cure it and to cause the said stresses in the curing resinoid to press annular portions of the resinoid progressively into said space of tapering cross-section to effect gripping engagement of said annular resinoid portions, respectively, against said two surfaces.

EDWARD VAN DER PYL.
